TERMINIONIC VALVE CIRCUITS

Filed Feb. 2, 1924

Inventor
PETER W. WILLANS.

By his Attorney *Frank J. Adams*

UNITED STATES PATENT OFFICE.

PETER WILLIAM WILLANS, OF TOWCESTER, ENGLAND, ASSIGNOR TO RADIO CORPORATION OF AMERICA, A CORPORATION OF DELAWARE.

THERMIONIC VALVE CIRCUITS.

Application filed February 2, 1924, Serial No. 690,223, and in Great Britain March 2, 1923.

This invention relates to thermionic valve circuits and its object is to provide an arrangement in which it shall be impossible for oscillations that may be set up by a valve 5 from being communicated to one of the circuits connected or coupled to the valve, which circuit is hereinafter called the defended circuit.

In order that my invention may be more 10 readily understood I will refer to the accompanying drawings in which Figs. 1, 2 and 3 are diagrammatic illustrations of arrangements embodying the inventions.

Figure 1 shows a wireless receiving system 15 employing a valve V, the adjustments of which may be such that it will oscillate for heterodyne reception. Valve V is shown as having input electrodes 1 and 2 and a plate 3. The feedback is provided by a coil 4 in the plate circuit which is magnetically coupled to a coil B in the grid circuit. The coil B is divided at the point 5 intermediate its ends into two portions 6 and 7. In such a case it is desirable that oscillations thus generated by 20 the valve should be excluded from the aerial circuit 8 which includes a variable inductance A for tuning it to the incoming signal. This is effected according to the invention by dividing the inductance B forming part of the 25 oscillatory circuit connected to the grid and by connecting the aerial to the point of division 5 of the inductance and also to the filament 1 and by inserting between the end 6 of the inductance remote from the grid and 30 the point 9 on the aerial where it is connected to the filament an impedance X to balance the impedance of the valve. When a grid leak and grid condenser G are used as in 35 Figs. 1, 2 and 3 the impedance X is equivalent to the combination of G plus the impedance of the valve. In the specification and claims an impedance equivalent to the valve 40 is intended to include this combination as well as its equivalents. This forms in effect a Wheatstone bridge of which the two parts 45 6 and 7 of the inductance B are two arms and the impedance X and the valve the other two

arms, while the aerial is connected to form a diagonal of the bridge. Thus when a balance is obtained in the bridge, oscillations in 50 B will not be transmitted to the aerial. In the four arm Wheatstone bridge shown points 5 and 9 constitute a pair of conjugate neutral points and the ends 6 and 7 of coil B or any two points along B having the same 55 potential, constitute an opposite pair of conjugate neutral points. The frequency of oscillation of the valve V may be controlled by the variable condenser F connected across the ends of coil B. 60

In place of connecting the aerial A to a point in the inductance B, I may connect it to a point between two condensers which are arranged in series between the grid of the valve and the impedance X as shown in Fig. 2. 65

Figure 3 shows a modified arrangement in which the oscillatory circuit containing the inductance B is connected to the grid 2 through the upper part 7 of an additional inductance C, the lower part 6 of which is 70 connected through the impedance X to the filament 1 of the valve V. In this case the impedance X consists of a valve similar to the valve V but of course unenergized. If the valve V is liable to pass grid current the 75 unenergized valve may be shunted across its grid and filament by a balancing resistance Q which therefore forms part of the compensating impedance. The plate of the unenergized valve may be connected to that of V in so 80 accordance with known practice in order to prevent potentials on the anode from setting up currents in the aerial.

The aerial A is coupled to the coil C electro- 85 magnetically but is screened from it electrostatically by an earth screen D.

Instead of the coil B being tuned by the condenser F as shown the coil E may be so tuned.

Having described my invention what I 90 claim is:

1. The combination with an electron discharge valve regeneratively connected, of a circuit associated therewith for impressing

signals on the input electrodes of the valve, a divided impedance having one end connected to the control electrode of said valve, and a circuit composed of two parallel branches, 5 one comprising the input electrodes of the valve and a portion of the impedance, the other branch comprising the other portion of the impedance and a balancing impedance equivalent to the input impedance of the 10 valve, said parallel branches being joined at the filament of the valve and at the midpoint of the impedance and said first-mentioned circuit being symmetrically disposed with reference to the two branches whereby the 15 first-mentioned circuit is defended from oscillations of the valve.

2. The combination with an electron discharge valve, of a circuit associated therewith for impressing signals on the input electrodes 20 of the valve, a divided impedance having one end connected to the control electrode of said valve, a circuit composed of two parallel branches, one comprising the input electrodes of the valve and a portion of the impedance, the other branch comprising the other portion of the impedance and a balancing impedance equivalent to the input impedance of the valve, said branches being joined at the cathode of the valve and the 25 midpoint of the impedance, and a tuning element between the junctions of the branches.

3. The combination with an electron discharge valve regeneratively connected, of a circuit associated therewith for impressing 35 signals on the input circuit of the valve, a divided impedance having one end connected to the control electrode of said valve, and a circuit composed of two parallel branches, one comprising the input electrodes of the 40 valve and a portion of the impedance, the other branch comprising the other portion of the impedance and a balancing impedance in the form of an unenergized valve similar to the first-mentioned valve, said branches being joined at the cathode of the valve and the 45 mid-point of the impedance and said first-mentioned circuit being symmetrically disposed with reference to the two branches whereby the first-mentioned circuit is defended from oscillations of the valve.

4. The combination with an electron discharge valve, of a circuit associated therewith having means for impressing signals on the input circuit of the valve, a divided impedance 55 having one end connected to the control electrode of said valve, and a circuit composed of two parallel branches, one comprising the input electrodes of the valve and a portion of the impedance, the other branch comprising the other portion of the impedance and a balancing impedance, said branches being joined at the cathode of the 60 valve and the midpoint of the impedance, and means for coupling the output circuit

of the valve to said divided impedance, said first-mentioned means being connected across the junctions of the branches whereby the first-mentioned circuit is defended from oscillations of the valve.

5. The combination with a vacuum tube, 70 of means for regeneratively coupling its input and output circuits, said means having associated therewith a divided impedance in said input circuit, and means, for preventing any effects of said regenerative coupling on a portion of said input circuit containing the divided impedance, comprising a pair of parallel circuits shunted around said portion, each of said parallel circuits containing one portion of said divided impedance and an 75 additional impedance, said additional impedances bearing the same ratio to each other as the portions of said divided impedances in the parallel circuits.

6. In signalling circuits the combination 85 of a bridge circuit including an electron tube having a plate and two input electrodes, said tube having input and output circuits with a feedback therebetween external to the tube, the input electrodes of said tube being 90 connected to points on one of the arms of the bridge and a source of signals impressed across a pair of conjugate points of said bridge circuit, said feedback being impressed on an opposite pair of conjugate points of 95 said bridge circuit.

7. A signalling circuit arrangement comprising in combination, a bridge circuit including a three electrode vacuum tube, a divided inductance and a balancing impedance, 100 said divided inductance being connected at one end to the grid of said tube and said balancing impedance connected between the other end of said inductance and the filament of the tube, the signal potential being impressed across a pair of conjugate points of the bridge and means for coupling the output of said vacuum tube to said divided inductance.

8. A circuit system comprising in combination, an input circuit, an output circuit, a vacuum tube having a plate, grid and filament, a circuit comprised of a divided impedance and a second impedance serially connected, the terminals of said circuit being connected respectively to said grid and filament whereby a closed mesh circuit is formed having a conjugate pair of neutral points, 115 said input circuit being connected across said pair of conjugate points, and said plate being electrically coupled to said mesh circuit and to said output circuit.

9. The combination with a valve having a control electrode and cathode, of an inductance connected to its control electrode, an impedance connected to an intermediate point of the inductance and to the cathode, and a balancing impedance connected between the 125

end of the inductance, which is remote from the control electrode, and the point where the impedance is joined to the cathode.

10. In combination, a bridge circuit including an electron tube having an anode control electrode and cathode and having a feedback between its input and output circuits, the control electrode and cathode of said tube being connected to points on one 10 arm of said bridge circuit and said feedback

being impressed across a pair of conjugate points on said bridge circuit.

11. In a combination, as defined in claim 9, said balancing impedance being an unenergized valve similar to the first valve. 15

12. In a signaling circuit arrangement, as defined in claim 7, said balancing impedance being an unenergized tube similar to the first tube.

PETER WILLIAM WILLANS.
